UNITED STATES PATENT OFFICE.

JAMES LAMBERT DISNEY, OF PHILADELPHIA, PENNSYLVANIA.

STEREOSCOPE.

1,244,843.

Specification of Letters Patent. Patented Oct. 30, 1917.

Application filed November 20, 1916. Serial No. 132,396.

To all whom it may concern:

Be it known that I, JAMES LAMBERT Disney, a subject of Great Britain, residing at Philadelphia, in the county of Philadelphia and State of Pennsylvania, have invented 5 certain new and useful Improvements in Stereoscopes, of which the following is a specification.

My invention consists of an improved 10 stereoscope, one of the objects being to provide a stereoscope which will be of simple construction and can be conveniently carried in the pocket.

Another object is to include in my improved 15 stereoscope a structure which provides a box or case capable of holding the other portions of the stereoscope when the latter is not in use.

A further object is to so construct my improved 20 stereoscope that it may be easily manipulated and can be manufactured and sold at a low cost.

These objects, and other advantageous 25 ends which will be described hereinafter, I attain in the following manner, reference being had to the accompanying drawings in which—

Figure 1 is a plan view of my improved stereoscope.

Fig. 2 is a section on the line *a—a* of 30 Fig. 1.

Fig. 3 is a section on the line *b—b* of Fig. 1.

Fig. 4 is a fragmentary section on a 35 slightly enlarged scale taken on the line *c—c* of Fig. 3.

Fig. 5 is a sectional view taken on the line *d—d* of Fig. 3 showing the construction 40 of the means for holding the lenses and their adjacent parts.

Fig. 6 is a perspective view of one of the handles employed for manually holding the stereoscope.

Fig. 7 is a perspective view of a lens retaining plate which I preferably employ.

Fig. 8 is a fragmentary section taken on the line *f—f* of Fig. 1.

Fig. 9 is a perspective view of my improved stereoscope in its open position ready 50 for use.

Fig. 10 is a fragmentary plan view showing a modified form of a portion of my invention.

Fig. 11 is a section on the line *e—e* of 55 Fig. 10.

Fig. 12 is a fragmentary section showing

a modified form of certain of the elements illustrated in Fig. 8.

Referring to Figs. 1 to 9 inclusive of my invention, 1 is a box made of sheet metal or other suitable material. The box comprises two elongated sections 2 and 3. These sections have their elongated sides 4 and 5 provided with longitudinally extending flanges 6 and 7 respectively which are discontinued 60 for a short distance throughout their length to provide notches 6^a and 7^a (see Fig. 1).

The sides 8 and 9 of the sections 2 and 3 extend longitudinally throughout the length of the sections and are hinged together as 70 shown at 10, so that the box sections may be folded one upon the other to provide a closure for any material placed thereon.

The ends 11 and 12 of the sections 2 and 3 are in the present instance held in place 75 by overlapped extensions 13 of the sides 4, 5, 8, and 9, and in the following description the ends 11 and 12 will be referred to as the rear ends of the box. The front ends 14 and 15 are of substantially the same construction as the rear ends 11 and 12 and provide hinges 16 and 17 on their inner surfaces for two lens-supporting plates 18 and 19 which are designed to be moved into an upright position as shown in full lines 85 in Figs. 1, 3, and 9, or to be folded downwardly into the box sections 2 and 3 as shown in dot-and-dash lines in Fig. 3.

The plates 18 and 19 have holes 20 and 21 formed therein to provide lens space, a portion 90 of the metal of said plates 18 and 19 being bent outwardly to form retaining flanges 22 and 23 for the sides of the lenses 24.

Flanged collars or sleeves 25 and 26 are secured to the outer surfaces of the lens supporting plates 18 and 19 by solder or other suitable means and are designed to surround the lenses 24. Each of the collars 25 and 26 has a bead 27 (see Figs. 3 and 5). These beads act as retaining means for ring shields 100 28, which are preferably made of flexible rubber tubes and shaped as clearly shown in Figs. 1 and 9 to conform to the contour of the eyes. These ring shields serve to protect the user of the stereoscope and also to 105 provide a seal to prevent light from entering the eyes of the user in a direction other than through the lenses 24. This insures a distinct reflection of the object or objects being viewed.

As a further means for retaining the lenses 24 in position, I provide plates 22^a which

have outer edges designed to be forced within the flanged collars 25 and 26. These plates 22^a have inwardly projecting top and bottom flanges 23^a and 23^b adjacent openings 5 21^a. The openings 21^a are slightly narrower than the height of the lenses 24 so as to provide a shoulder for the lenses as clearly shown in Fig. 5.

The edges of the lens supporting plates 10 18 and 19, which are adjacent the sides 8 and 9 of the box sections 2 and 3, are connected by hinges 29 and 30 to two rearwardly extending partition plates 31 and 32. These partitions, when the stereoscope is 15 ready for use, occupy upright positions respectively against the sides 8 and 9 and adjacent their rear ends are provided with short flanges 33 and 34 which extend transversely of the sections 2 and 3 and substantially parallel with the plates 18 and 19 20 when the latter are in their upright positions.

The plates 31 and 32 have narrow tongues 35 and 36 which are located adjacent said 25 sides 8 and 9 of the box sections 2 and 3 (see Figs. 1, 3, 4, and 9). Each of the tongues 35 and 36 is provided with an elongated slot 37 which registers with slots 38 and 39 which are respectively cut in the sides 8 and 9 of 30 the box (see Figs. 1 and 4).

A resilient finger 40 is secured to the inner surface of the side 8 by means of a rivet 41 or other suitable means and has its free end 42 linked to a binding or locking pin 43, the 35 latter being designed to be projected through the slots 37, 38, and 39 when the box sections 2 and 3 are opened and is provided at its free end with an eye 44 into which extends the end of a hook 45, the latter being 40 pivoted at 46 to the inner surface of the side 9 of the box section 3, so that when said hook 45 engages the eye 44, the box sections 2 and 3 will be held in an open or spread position with their sides 8 and 9 engaging and 45 it will be impossible to close said sections until the hook 45 is removed from the eye 44, and the pin 43 withdrawn from the slots 37 to 39 inclusive.

It will be of course understood that the 50 pin 43 is made of a pre-determined length according to the thicknesses of the different members through which it is projected, so that the hook 45 will really act to place a slight tension on the pin to prevent the parts 55 from accidentally loosening.

For convenience of description, the portions 47 and 48 of the box sections 2 and 3 will be termed the bottom and top, but it will be understood that when said sections 60 are folded and since they are of substantially the same construction, there will be practically no top or bottom.

The portions 47 and 48 have openings 49 and 50 which are designed to receive handles 65 51 and 52, and these openings are preferably

made of the same contour as the handles as clearly shown in the drawings. The openings 49 and 50 are extended part way through the sides 8 and 9 as clearly shown in Fig. 8.

Each of the handles 51 and 52 is provided with an ear 53 which extends at right angles thereto as clearly shown in Fig. 6. These handles are hinged to the box sections at 70 54, so that when the handles are in a pendant position as shown in Figs. 2 and 9, the ears 53 will be in the same plane with the portions 47 and 48 of the box sections 2 and 3, and will lie directly under the partition plates 31 and 32, and since the latter are 75 held rigidly in their upright positions by the locking pin 43 as above mentioned, the handles 51 and 52 will be locked in said pendant position and cannot move on their pivots until the partition plates 31 and 32 80 are moved on their hinges 29 and 30 toward the lens supporting plates 18 and 19 so as to free the ears 53 and permit the handles 51 and 52 to be turned on their pivots.

The handles 51 and 52 are locked in their 90 positions within the openings 49 and 50 in the following manner:—After the partition plates 31 and 32 are moved on their hinges 29 and 30 toward the lens supporting plates 18 and 19, the latter are folded downwardly 95 into the box sections 2 and 3 as shown in the dot-and-dash position in Fig. 8, it being understood that when the handles 51 and 52 are within the openings 49 and 50, the ears 53 will be in position within the extensions 100 of the openings 49 and 50 in the sides 8 and 9 as clearly shown in Fig. 8. Therefore, when the lens supporting plates 18 and 19 and the partition plates 31 and 32 are folded 105 into the sections, the ears 53 will be confined 110 between the hinged edges of said latter plates and the sides 8 and 9. In other words, the lens supporting plates and the partition plates act as a stop to prevent movement of the handles on their hinges and said handles 115 are thereby locked.

An object holder 55 is preferably made of pressed sheet metal and formed into a frame as clearly shown in Fig. 9. The frame consists of a back 56 having forwardly projecting end portions 57 and 58. The end portions have flanges 59 and a bottom 60 has a front flange 61. This frame is especially adapted for holding cards, pictures or other objects to be viewed, the flanges 59 120 and 61 and the back 56 tending to confine the cards in a position to be properly viewed through the lenses 24.

The bottom 60 is slit to provide a clip 62, said clip consisting of downwardly extending portions 63 which are spaced apart and designed to straddle the hinged sides 8 and 9 of the box sections 2 and 3 to slide longitudinally thereon.

Lips 64 are hinged at 65 to opposite ends 130

57 and 58 of the object holder 55, and are designed to engage under the longitudinally extending flanges 6. The lips 64 have inwardly projecting extensions 66 designed to 5 abut the under surface of the bottom 60, and said lips are so located that they frictionally engage the under surfaces of the flanges 6 and 7 to provide a steady support for the holder.

10 A handle 67 is provided on the holder 55 and in the present instance consists of a loop of wire which has eyes 68 in its ends pivotally hung on trunnions 69. The handle 67 facilitates the movement of the holder 15 longitudinally of the box sections toward and from the lenses 24 to secure the desired focus.

A detachable spring 70 has a hooked end 71 designed to engage the upper edge of the back 56, the portion 72 of the spring being bent forwardly and designed to keep pictures or cards which are placed within the holder 55 against the flanges 59 and 61, however, if the holder is entirely filled with pictures or cards, the spring 70 may be removed by raising the hooked end 71. It will thus be noted that when only a few cards are positioned within the holder, the spring 70 acts to hold them in an upright position 30 against the flanges 59 and 61.

In the use of stereoscopes, two pictures of the object or scene to be viewed are usually provided, one on each side of a vertical center line on the cards containing the 35 pictures, and since the pictures are viewed by both eyes, means is generally provided to obscure the direct dividing line from the vision so that the pictures will appear as a unitary picture to the observer. I accomplish this end by the provision of the flanges 33 and 34 on the inner ends of the partition plates 31 and 32.

When not in use, the lens supporting plates and partition plates are folded into 45 the box sections as above described, and the holder 55 may be removed by sliding it into register with the notches 6^a and 7^a in the flanges 6 and 7, when it may be lifted bodily, the lips 64 passing out through said 50 notches. After the holder has been thus removed, it can be placed within the box sections, it being of course understood that the handle sections are moved into the openings 49 and 50 as above described. The box sections 2 and 3 may then be closed and locked in a closed position by any suitable clamping means.

In the form of my invention shown in Figs. 10 and 11, I have shown a modified 60 form of box in which sections 73 and 74 are hinged together at 75 and 76 respectively. The sides 77 and 78 are flanged longitudinally at 79 and 80 and are similar to the flanges 6 and 7 above described in 65 connection with the box sections 2 and 3.

In this modification of my invention, the portion 81 provides one side of the box when the latter is folded, and when in its open position a slot 82 therein forms a guide-way for depending members 83 in an object 70 holder 84, the latter is of the same general construction as the object holder 55 above described with the exception of the construction of its lips 85 which are hinged to the sides thereof and extensions 86 thereon are substantially at right angles to engage the ends of the holder. 75

In this construction, the holder 84 is slideable along the surfaces 87 and 88, and the extensions 86 of the lips 85 serve to hold 80 the holder in position and also serve to hold the box sections in their extended position, since it is impossible to remove the holder until the lips 85 are manually removed from under the flanges 79 and 80. 85

In Fig. 12 I have shown a modification of the structure shown in Fig. 8, but instead of having the openings 49 and 50 extend into the sides 8 and 9, they terminate short of said sides, and the ears 53 of the handles 90 51 and 52 engage the inner surfaces of the sides 8 and 9 when said handles are moved into the openings 49 and 50. The position of the ears 53, when the handles 51 and 52 are within the openings 49 and 50, are 95 shown in dot-and-dash lines in engagement with the inner surfaces of said sides 8 and 9.

My invention is of particular value to travelers, business men, and salesmen, but it will be understood that it may be used 100 advantageously by any one who desires a stereoscope which may be conveniently carried in the pocket and which will be compact, durable, and require but little space to carry it. 105

In certain of the claims I have used the term "a box of fixed length" by which is implied a box whose length is not altered, but on the contrary is the same both when the box is closed and open ready for use, the 110 length of the box being considered as the distance between the rear end adjacent the object holder and the front end which is adjacent the front of the lenses.

While I have described my invention as 115 taking a particular form, it will be understood that the various parts of my invention may be changed without departing from the spirit thereof, and hence I do not limit myself to the precise construction set forth, 120 but consider that I am at liberty to make such changes and alterations as fairly come within the scope of the appended claims.

Having thus described my invention, what I claim as new and desire to secure by Letters Patent is:

1. A stereoscope comprising a box having elongated sections hinged together and extending from front end to rear end of the box, lenses supported by said box adjacent 130

- the front end thereof, and an object holder movable toward and from said lenses in the direction of the length of said sections, substantially as described.
- 5 2. A stereoscope comprising a box having elongated sections hinged together and providing a guideway extending from the front end to the rear end of the box, lenses supported by said box adjacent the front end 10 thereof, and an object holder movable toward and from said lenses and along said guideway, substantially as described.
- 15 3. A stereoscope comprising a box having sections hinged together and extending from front end to rear end of the box, lens supporting means carried by said box sections adjacent the front end of the box and movable into and out of said sections, means for locking said lens supporting means in its 20 outward position, lenses in said supporting means, and an object holder movable toward and from said lenses in the direction of the length of said box sections, substantially as described.
- 25 4. A stereoscope comprising a box having elongated sections hinged together and extending from front end to rear end of the box, plates hinged to the interior of said box sections and foldable therein, lenses in 30 said plates, and an object holder movable toward and from said lenses in the direction of the length of said sections, substantially as described.
- 35 5. A stereoscope comprising a box of fixed length from front end to rear end, lenses having their focal distance extending in the direction of said length of the box and located adjacent said front end, and an object holder movable in the direction of the length 40 of said box toward and from said lenses, substantially as described.
- 45 6. A stereoscope comprising a box of fixed length from front end to rear end, lenses having their focal distance extending in the direction of said length of the box and located adjacent said front end, and an object holder movable in the direction of the length 50 of said box toward and from said lenses, said box having a portion providing a slide-way for said object holder in said latter direction, substantially as described.
- 55 7. A stereoscope comprising a box having elongated sections, one of the sides of each section being hinged together, a lens supporting plate hinged within each section and foldable into said sections, lenses in said plates, other plates hinged to said first plates and operative to hold said first plates in an upright position, an object holder slidably 60 connected to but detachable from said box, and means for locking said second-mentioned plates in a position to hold said first plates in their upright positions so that the object holder is in line with said lenses, substantially as described.
- 65 8. A stereoscope comprising a box having elongated sections, one of the sides of each section being hinged together, a lens supporting plate hinged within each section and foldable into said sections, lenses in said plates, other plates hinged to said first plates and operative to hold said first plates in an upright position, an object holder slidably connected to but detachable from said box, common means for locking said second-mentioned plates and the box sections in their operative positions so that the object holder is in line with said lenses, substantially as described. 70
9. A stereoscope comprising a box having elongated sections, one of the sides of each section being hinged together, a lens supporting plate hinged within each section and foldable into said sections, lenses in said plates, other plates hinged to said first plates and operative to hold said first plates in an upright position, an object holder slidably connected to but detachable from said box, said second-mentioned plates and the hinged sides of the box sections having slots therein, a member movable through said slots, and means for securing said member to lock the second-mentioned plates and the box sections in their operative positions so that the object holder is in line with said lenses, substantially as described. 75
10. A stereoscope comprising a box having elongated sections, one of the sides of each section being hinged together, a lens supporting plate hinged within each section and foldable into said sections, lenses in said plates, other plates hinged to said first plates and operative to hold said first plates in an upright position, an object holder slidably connected to but detachable from said box, said second-mentioned plates and the hinged sides of the box sections having slots therein, a resilient finger secured to the inner surface of one of said box sides, a pin movably supported on said finger and designed to be 80 projected through said slots, said pin having an eye formed in its free end, a hook mounted on the inner surface of the other of said box sides and movable into said eye of the pin to lock the second-mentioned plates and the box sections in their operative positions so that the object holder is in line with said lenses, substantially as described. 85
11. A stereoscope comprising a box having elongated sections, one of the sides of each section being hinged together, a lens supporting plate hinged within each section and foldable into said sections, lenses in said plates, other plates hinged to said first plates and operative to hold said first plates in an upright position, an object holder slidably connected to but detachable from said box, said second-mentioned plates having flanges at positions remote from their hinged connection with the first-mentioned plates, 90
- 100
- 105
- 110
- 115
- 120
- 125
- 130

said object holder being in line with said lenses, substantially as described.

12. A stereoscope comprising a box having elongated sections, one of the sides of each section being hinged together, a lens supporting plate hinged within each section and foldable into said sections, lenses in said plates, other plates hinged to said first plates and operative to hold said first plates in an upright position, openings formed in said box sections, handles pivoted to said box sections and movable into and out of said openings, said handles having ears thereon designed to be engaged by the lower edge of said second-mentioned plates and thereby to hold the handles in their operative positions out of said openings, means for locking the box sections in an open position and to lock the second-mentioned plates in said latter position to lock the handles, said second-mentioned plates when freed by the locking means being movable on their hinges to free said ears on the handles to permit them to be moved into the openings in the box sections, substantially as described.

13. A stereoscope including a box made in sections hinged together, each of said sections having a side flange, said flanges forming guide-ways when the box is open, an object holder, means on said object holder for frictionally engaging said flanges and operative to permit sliding movement of said holder but to prevent accidental movement thereof, substantially as described.

35 14. A stereoscope including a box having flanges forming guideways, an object holder, means on said object holder for frictionally engaging said flanges and operative to permit sliding movement of said holder but to

prevent accidental movement thereof, said object holder having a clip thereon, said box having a portion providing a guideway for said clip, substantially as described.

15. A stereoscope comprising a box having elongated sections, one of the sides of each section being hinged together, a lens supporting plate hinged within each section and foldable into said sections, lenses in said plates, other plates hinged to said first plates and operative to hold said first plates in an upright position, openings formed in said box sections, handles pivoted to said box sections and movable into and out of said openings, said handles having ears thereon designed to be engaged by the lower edge of said second-mentioned plates and thereby to hold the handles in their operative positions out of said openings, means for locking the box sections in an open position and to lock the second-mentioned plates in said latter position to lock the handles, said second-mentioned plates when freed by the locking means being movable on their hinges to free said ears on the handles to permit them to be moved into the openings in the box sections, 65 the hinged plates when in said folded position being operative to lock said ears in a position to hold the handles within their openings in the box sections, substantially as described.

In testimony whereof I have signed my name to this specification in the presence of two subscribing witnesses.

JAMES LAMBERT DISNEY.
